C. M. MAYO

PROCESS OF FORMING RECEPTACLES

Filed Jan. 26, 1923

INVENTOR.
CHARLES MATTHEW MAYO.

BY
Charles Matthew Mayo
ATTORNEYS.

UNITED STATES PATENT OFFICE.

CHARLES MATTHEW MAYO, OF INDIANAPOLIS, INDIANA.

PROCESS OF FORMING RECEPTACLES.

Application filed January 26, 1923. Serial No. 615,025.

To all whom it may concern:

Be it known that I, CHARLES MATTHEW MAYO, a citizen of the United States, and a resident of Indianapolis, county of Marion, 5 and State of Indiana, have invented a certain new and useful Process of Forming Receptacles; and I do hereby declare that the following is a full, clear, and exact description thereof, reference being had to the accompanying drawings, in which like numerals refer to like parts.

This invention relates to a process of forming or molding a cooling chest or like receptacle formed of a plastic composition, 15 wherein the same may be provided with water chambers and communicating passages about its sides, end and bottom so that the water chambers or passageways may be filled from a single opening and may circulate about the walls thereof. Reference may be had to the application of Charles M. Mayo, filed October 23, 1922, Serial No. 596,372 for iceless refrigerating chest.

The principal object of the invention 25 resides in the method of casting the walls, and particularly the bottom of the structure, and the means of forming communicating passageways within said walls and bottom, whereby the cooling chest or like receptacle may have its walls and bottom cast 30 integral and provided with strengthening ribs, while having formed enclosed and entirely within said walls and bottom, communicating passageways or water containing chambers.

The full nature of this invention will be understood from the accompanying drawings and the following description and claims.

40 In the drawings Fig. 1 is a perspective view of the cooling chest. Fig. 2 is a central vertical section through the mold and extending longitudinally thereof, showing the chest partially formed in inverted position. Fig. 3 is the same as Fig. 2 showing the method of forming the bottom upon the chest. Fig. 4 is a section taken on the line 4—4 of Fig. 3. Fig. 5 is a plan view looking down on the structure shown in Fig. 2. 45 Fig. 6 is an end elevation of the mold shown in Fig. 2. Fig. 7 is an end elevation of the mold shown in Fig. 3.

In the drawings there is shown a cooling 55 chest comprising a box-like structure, supported by the legs 10 and having the sides 11 and ends 12 which are provided with

recessed decorative portions 13. Said sides and ends are provided about their top with an offset forming the shoulder 14 for receiving a suitable lid, not shown herein. 60 The box is formed of a specially prepared plastic composition which is sufficiently porous to permit the comparatively rapid evaporation of a liquid, such as water, for providing a cooling effect to the interior of 65 the box. To this end it is necessary to provide water containing chambers in the sides, end and bottom, all of which communicate with each other for permitting the free circulation of water for absorption and evaporation. 70

The process of casting and forming the box so that the walls and bottom thereof will be formed integral with each other with the necessary chambers or passageways cast 75 therein, comprises the formation of an outer shell or mold 15 comprising two diagonally opposed removable sections. Each section of the mold 15 consists of one end and a side, and is formed of suitable metal plate 80 provided with an angularly extending flange 16 at diagonally opposite corners so arranged as to be removably secured by the bolts 17 to similarly abutting flanges on the corresponding diagonally opposed section. 85 The inner face of each of the sides of the outer mold 15 is provided with raised surfaces 18 for forming the decorative panel recess 13, as shown in Fig. 1. After the sections of the outer mold 15 are secured together by the bolts 17 so as to form a rectangular mold, it is placed on the pallet board 19 which has its edges offset, as shown in Figs. 2 and 3, for forming the offset 90 14 about the top of the chest. 95

Positioned within the outer mold 15 there is an inner mold 20 of similar dimensions so as to fit within the outer mold and be positioned thereover a distance equal to the desired thickness of the surrounding walls 100 to be cast. Said inner mold is provided with a top plate 21, and rests upon the raised portion of the pallet board 19. Upon the two molds 15 and 20 being positioned upon the pallet board, the composition 22 to be molded is poured between the sides thereof and tamped and pressed down in the usual manner. The end core plates 23 and the side core plates 24 are then placed in position. Said core plates are formed of 105 metal of a thickness equal to the desired width of the passages or chamber, and of 110

sufficient length to extend out of the forms so as to permit them to be readily grasped through the holes 25 formed near the outer ends thereof. Said core plates are forced downwardly through the material 22 so that the end plates 23 abut the surface of the pallet board, while the side plates are withheld from the pallet board so that the lower ends thereof are spaced from the surface. For centering the plates, the inner bolts 26 and outer bolts 27 are provided, which screw through the forms 20 and 15 respectively so as to engage the sides of said core plates and space them properly 15 between said forms.

After the material 22 has set a sufficient length of time with the core plates therein, so as to hold its shape and be self-supporting, the plates 23 and 24 are withdrawn, leaving 20 a corresponding chamber or passage 28, the material remaining set in the form shown in Fig. 2. Upon the withdrawal of the plate, the screw bolts 27 are removed and the hole left thereby is plugged up by inserting the material 22 therein. The form is then made ready to mount the bottom thereon. For forming the chamber or passage in the bottom of the chest, the core plates 30 are employed, which are adapted 30 to extend through the slots 31 in the outer form 15. Said plates, after being inserted through said slots, are laid upon the material 22 supported on the top 21 of the frame 20 so that the further edge of the plate 30 is flush with the end chambers or 35 passages 28. The material is then built up to a level with the top surface of the plates 30, joining said plates with each other and with the side chambers or passages 28, as shown in Figs. 2 and 5 and by dotted lines in Fig. 4. The built up portion of the material leaves a communicating passage 34 between them over which a thin zinc plate 35 is mounted. The composition 22 is then placed on top of the plates 30 and the zinc plates 35 and provided with an embedded 40 strengthening wire mesh 36. The legs 37 are then built up and silent domes 38 are embedded therein for supporting the chest when finished. After the material formed 45 on the bottom has become set, and of sufficient strength to be self-supporting, the plates 30 are pulled out through the slots 31, leaving a chamber or passage in the bottom which is in communication with the end 50 passages 28 and also in communication between themselves and the side passages 38 through the passages 34 left open by the zinc plates 35.

After the composition has become thoroughly hardened, the mold is removed from the pallet board, the bolts 17 removed from the flanges 16 and the outer mold 15 is taken off. The chest is then set upright, and the screw bolts 26 are removed. The

inner mold 20 may then be lifted out and the holes left by the screw bolts 26 may be plugged up. The chest is then ready to be finished off in any suitable manner and colored, after which a suitable top may be 70 placed thereon. It will be observed that the chambers or passages formed by the several core plates and zinc plates 35 will be inter-communicating through the bottom of the chest so that there may be a free circulation 75 of water to all the walls thereof.

The invention claimed is:

1. The process of forming a receptacle having a plurality of inter-communicating chambers formed in the walls thereof, consisting of mounting an inner form within and spaced from an outer form, filling the space between said forms with a plastic material, embedding therein a core plate adapted to be pulled therefrom leaving the desired chamber formed therein, and screwing into said forms means for spacing said plate therefrom. 80

2. The process of forming a receptacle having a plurality of inter-communicating chambers formed in the walls thereof, consisting of mounting an inner form within and spaced from an outer form, filling the space between said forms with a plastic material for forming side walls, embedding therein a core plate adapted to be pulled therefrom leaving the desired chamber therein, providing a horizontal bottom supporting plate on the inner mold for supporting the composition formed thereon, 90 mounting thereover a horizontal core plate, forming a layer of material over said core plate, and slidably removing said plate upon said material becoming set, whereby a chamber will be left formed in the bottom and in communication with the chamber formed in the sides. 95

3. The process of forming a receptacle having a plurality of inter-communicating chambers formed in the walls thereof, consisting of mounting an inner form within and spaced from an outer form, filling the space between said forms with a plastic material for forming side walls, embedding therein a core plate adapted to be pulled therefrom leaving the desired chamber therein, providing a horizontal bottom supporting plate on the inner mold for supporting the composition formed thereon, building the material up so as to provide horizontal passageways between the built up portions in communication with the chambers formed in the walls, mounting thin plates on said built up portions so as to protect said passageways therebetween, and covering the same with the composition whereby the chambers in said walls will be in communication with each other through said passageway so formed. 100

4. The process of forming a receptacle 110

115

120

125

130

- having a plurality of inter-communicating chambers formed in the walls thereof, consisting of mounting an inner form within and spaced from an outer form, filling the
5 space between said forms with a plastic material for forming side walls, embedding therein core plates adapted to be pulled therefrom leaving the desired chambers therein, providing a horizontal bottom plate
10 on the inner mold, building the material up so as to provide horizontal passageways between the built up portions in communication with the chambers formed in the walls, mounting thin metal plates on said built
up portions so as to protect said passageways therebetween, inserting a core plate upon said material adjacent said built up portions and passageways so as to form a chamber in the bottom in communication with said passageways and the chamber
15 formed in the wall, mounting a layer of the composition upon said core plate and metal plates, and withdrawing said core plate by sliding it therefrom after said composition has become set. 25

In witness whereof, I have hereunto affixed my signature.

CHARLES MATTHEW MAYO.
